UNITED STATES PATENT OFFICE.

EDWIN L. LLOYD, OF PHILADELPHIA, PENNSYLVANIA.

BOTTLE-STOPPER.

SPECIFICATION forming part of Letters Patent No. 603,908, dated May 10, 1898.

Application filed May 8, 1896. Renewed April 8, 1897. Serial No. 631,318. (No model.)

To all whom it may concern:

Be it known that I, EDWIN L. LLOYD, a citizen of the United States, residing in Philadelphia, Pennsylvania, have invented certain 5 Improvements in Bottle-Stoppers, of which the following is a specification.

The object of my invention is to provide a cheap and simple form of bottle-stopper designed to prevent refilling of the bottle, and 10 this object I attain in the manner hereinafter set forth, reference being had to the accompanying drawings, in which—

Figure 1 is a sectional view of part of a bottle-neck with stopper therefor constructed in 15 accordance with my invention. Fig. 2 is a side elevation of the stopper detached from the bottle-neck. Fig. 3 is a view showing in elevation certain parts of the stopper detached from each other. Fig. 4 is a view of 20 the valve of the stopper in a different position from that shown in Fig. 1. Figs. 5, 6, and 7 are perspective views illustrating the construction of the valve of the stopper, and Fig. 8 is a view illustrating another form of 25 stopper embodying my invention.

In Fig. 1, A represents a tubular cork fitting snugly to the bottle-neck, the central opening of the cork receiving a tube a, preferably of glass, which has a flange or collar 30 b, and above the same a smaller tube d, the latter fitting into the central opening of a cap B, but not extending to the top of said opening.

In the inner side of the wall of the opening 35 in the cap B are formed a series of channels f, which communicate at their lower ends with a space g, formed between the flange b of the tube a and the beveled under side of the cap B, other channels i, formed in the 40 outer face of the cap B, also communicating with this space g, so that any liquid passing through the tube a d into the opening of the cap B can find its way through the channels f, space g, and channels i, and can flow from 45 the mouth of the bottle.

On the cap B are lugs or projections m for the support of a series of wires n, which, as 50 shown in Figs. 1 and 2, are carried down on the outer side of the cork A and pass behind a label D, applied to said cork, the lower ends

of the wires being bent upward on the outer side of the label, so that any attempt to remove the cap B will result in pulling the wires through the label, and will thus mutilate the same and show that the stopper has been 55 tampered with.

In the lower portion of the tube a is fitted a tubular cork s, to which is secured, by means of an internal tube t, the lower portion of a tube w, of rubber, waterproof-cloth, or paper, 60 or other available material of a flexible character, the outer end of this tube forming lips which will open to any flow of liquid outwardly through the tube, but will close and prevent any flow of the liquid into the tube. 65

The valve w is preferably constructed, as shown in Figs. 5, 6, and 7, by cutting a piece of thin flexible waterproof material to the shape shown in Fig. 5 and folding it over upon itself on a line about midway of its 70 length, as also shown in said figure. The projecting side flaps w' are then folded over upon and secured to the body, as shown in Fig. 6, so as to form a tube having at the outer end flat lips w², connected at the ends. 75

In one side of the tube are formed a series of openings w³ or other suitable form of vent, said vent being normally covered by a flap-valve w⁴, preferably of the same material as the main valve and secured in position by 80 passing a stem w⁵ through an incision formed in the body of said main valve and cementing it in place on the inner side of the latter.

Secured to the free end of the flexible tubular valve w is a weight x, which when the 85 bottle is inverted, so as to pour out its contents, will tend to straighten said valve, as shown in Fig. 4, and permit of the escape of liquid therefrom; but when the bottle is held in an upright or upwardly-inclined position 90 the valve will fall by gravity, so as to cause the folding or kinking of the flexible tube, thus closing one side of the tube against the other and effectually preventing the inflow of liquid through said tube. 95

When the bottle is inverted and the valve w distended by the flow of liquid therethrough, air can pass beneath the valve w⁴ and through the openings w³, so as to enter the bottle as the liquid flows therefrom; but any 100

attempt to pass liquid into the bottle will cause the closing of the valve w^4 and the retention of the same in a closed position.

A valve such as I have described is of cheap 5 and simple character and has shown itself to be very effective for the purpose intended.

In that embodiment of my invention shown in Fig. 7 the opening in the cork A' is decreased in diameter at the bottom, so as to

- 10 provide for the reception of the inner portion of the valve w , and on the top of the cork rests a hollow cap B' with three external channels i' , each communicating at its lower end with a chamber within the cap. This cap is
- 15 intended to be secured in the bottle-neck by any suitable cement; but even in the absence of this method of fastening any attempt to remove the cap by means of a wire or other implement inserted in one of the channels i' will
- 20 simply have the effect of tilting the cap so as to cause it to bind in the neck and prevent its removal therefrom.

Having thus described my invention, I claim and desire to secure by Letters Patent—

- 25 1. A bottle-stopper having a projecting valve consisting of a tube of flexible material secured at one end and provided at the free end with a weight, whereby the tube will
- 30 be straightened when the bottle is held with the mouth downward, the weight falling by gravity when the bottle is held with the mouth upward, so as to cause the folding or kinking of the flexible tube, substantially as
- 35 specified.

2. A bottle-stopper having a projecting

valve with flexible lipped outlet, one or more air-inlet openings being formed in the valve behind said outlet, substantially as specified.

3. A bottle-stopper having a projecting 40 valve with flexible lipped outlet, said valve also having formed in it one or more air-inlet openings with flap-valve for closing the same, substantially as specified.

4. A bottle-stopper having a projecting 45 valve consisting of a strip of flexible waterproof material folded upon itself and having the edges united throughout a part of its length, the edges at and near the fold being free so as to form lips, substantially as speci- 50 fied.

5. A bottle-stopper having a projecting valve consisting of a strip of waterproof material folded upon itself and having overlapping edges throughout a portion of its extent, 55 the portion in which the edges are not overlapped forming opposite lips, substantially as specified.

6. A bottle-stopper consisting of a tubular block having an external label visible through 60 the bottle-neck, a detachable cap having projecting lugs, and depending wires hung to said lugs and engaging with the label, substantially as specified.

In testimony whereof I have signed my 65 name to this specification in the presence of two subscribing witnesses.

EDWIN L. LLOYD.
